UNITED STATES PATENT OFFICE.

ALBERT EDWARD JOHN SMITH, OF BATTERSEA, LONDON, ENGLAND.

RESILIENT HUB FOR WHEELS.

No. 920,404.

Specification of Letters Patent.

Patented May 4, 1909.

Application filed April 3, 1907. Serial No. 366,182.

To all whom it may concern:

Be it known that I, ALBERT EDWARD JOHN SMITH, residing at 157 Bridge road, Battersea, London, S. W., England, have invented 5 certain new and useful Improvements in Resilient Hubs for Wheels; and I do hereby declare the following to be a full, clear, and exact description of the invention, such as will enable others skilled in the art to which it 10 appertains to make and use the same.

This invention relates to a new or improved resilient hub for the wheels of motor and other road vehicles, the object being to provide a hub of this class of comparatively 15 simple construction, wherein the shocks due to the vehicles passing over inequalities of the road are absorbed by flexible cushions in an improved manner so that the give and return of the cushions is unaccompanied by 20 any jar, and a positive, although at the same time flexible, drive is obtained; furthermore, means is provided whereby internal friction in this hub is reduced to a minimum. 25 In specifying my invention, however, I wish it to be clearly understood that I am aware of the previous employment of a ring or rim carrying a pneumatic cushion, the said ring being free to rotate around the axle sleeve of 30 the wheel, with flanges carried by the said sleeve between which the said ring or rim is arranged, but this form of construction has been found unsatisfactory in practice and my invention has been designed to overcome 35 the defects hitherto experienced, by constructing the device as hereinafter set forth.

In order that this invention may be fully understood it will now be described with reference to the accompanying drawings, in which:—

40 Figure 1 is a side elevation of a device constructed according to this invention, having a side plate removed and the inner plate hereinafter referred to, broken partly away, for clearness, Fig. 2 is a transverse section 45 of the complete device taken as on line xx (Fig. 1.).

In carrying this invention into practical effect, two plates a , a^1 are mounted upon a tubular sleeve b running upon the wheel axle 50 in the usual manner, these plates being retained parallel and a suitable distance apart by a convenient number of distance pieces or spindles c arranged circumferentially. The plate a^1 is suitably secured to a flange b^1 55 on the tubular sleeve b . Upon the said tubular sleeve b , between the two plates a , a^1 , is

mounted a cushion d of rubber suitably bored or perforated as at d^1 to impart the necessary resiliency and upon the surface of this cushion d bears the internal surface of a hollow drum e also mounted between the plates a , a^1 , their distance pieces or spindle c passing through chambers e^1 formed in the material of the said drum e and each carrying a small rubber cushion f of approximately barrel 60 shape the largest diameter of which fits within its respective chamber which is extended in both directions radially to allow of the expansion of the cushion f as hereinafter described and the chambers e^1 open 65 completely to the center of the drum as shown so that a series of comparatively small bearing surfaces is presented to the central cushion d which has the effect of improving its resiliency and permitting greater 70 expansion or distortion. The drum e forms a spoke-ring or support for the wheel spokes, and the bearing surfaces or projections p which bear on the annular cushion or buffer have passages p^1 between them into which 75 the cushion or buffer can expand and which communicate with the chambers e^1 and which are arranged radially.

The wheel is built up upon the drum e the extremities of the spokes entering recesses e^2 80 formed in the periphery thereof, and has the drive imparted from the hub, through the plates a , a^1 , and the small rubber cushions f contained within the chambers e^1 of the drum e , and these buffers f although imparting a positive drive are so formed that they 85 "give" sufficiently to prevent shock while upon inequalities in the road being negotiated the central rubber cushion d is depressed by the drum and absorbs the shock, the 90 small cushions f also assisting in this respect. As shown it is preferred to arrange the cushions f in alternate recesses e^1 and if desired the remaining recesses may be occupied by 95 spare buffers ready for use in case of need. It is preferable in all cases to provide buffers 100 or cushions d and f with liners d^2 , f^1 respectively in order to reduce wear to a minimum and facilitate removal and replacement of the cushion upon the sleeve b and spindles c . 105

In order that friction may be minimized a ball race may be provided between each side of the drum e and its respective side plate, and as shown pockets or recesses g pass completely through the said drum each 110 containing a spring g^1 in compression at each extremity of which is arranged a ball and

these balls g^2 are thus forced outward against restraining plates h provided with holes or perforations h^1 through which the balls protrude sufficiently to bear against 5 the side plates a, a^1 , upon which they run, and the plates a, a^1 are provided with annular channels or grooves a^2 which serve as ball races which are of sufficient width to allow 10 of the necessary rolling motion of the ball.

Having now described my invention what 10 I claim as new and desire to secure by Letters Patent is:—

In a wheel-hub, the combination, with an axle-tube, and two side-plates; of a series of 15 driving-spindles secured between the said side-plates, elastic cushions transmitting the driving pressure and encircling the said spindles, an annular elastic buffer encircling the

said axle-tube, and a spoke-ring provided with a series of chambers the middle portions 20 of which engage with the side portions of the said cushions, said spoke-ring having also a series of projections which bear on the said annular buffer and having also a series of 25 radial passages which extend on each side of the said cushions in the said chambers and between the said projections, for the said cushions and annular buffer to expand into when compressed.

In testimony whereof I affix my signature, 30 in presence of two witnesses.

ALBERT EDWARD JOHN SMITH.
